CLAIM

The ornamental design for a digital video camera, as shown and described.

DESCRIPTION

FIG. 1 is a front view of a digital video camera showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a front, top and left side perspective view thereof, and,

FIG. 8 is a rear, top and right side perspective view thereof. The broken lines in the drawings illustrate portions of the digital video camera which form no part of the claimed design.

1 Claim, 8 Drawing Sheets(56)
